(57) **CLAIM**

The ornamental design for an umbrella light stand, as shown and described.

DESCRIPTION

FIG. 1 is a top perspective view of a umbrella light stand. FIG. 2 is a bottom perspective view of the umbrella light stand of FIG. 1.

FIG. 3 is a front view of the umbrella light stand of FIG. 1; FIG. 4 is a back view of the umbrella light stand of FIG. 1; FIG. 5 is a left view of the umbrella light stand of FIG. 1; FIG. 6 is a right view of the umbrella light stand of FIG. 1; FIG. 7 is a top view of the umbrella light stand of FIG. 1; and,

FIG. 8 is a bottom view of the umbrella light stand of FIG. 1.

The broken line disclosure represents portions of the stand which form no part of the claimed design.

1 Claim, 8 Drawing Sheets
